UNITED STATES PATENT OFFICE

EDGAR C. MESSERSMITH, OF BUFFALO, NEW YORK.

TRIPOD FOR MOUNTING GUNS, &c.

1,331,116.

Specification of Letters Patent. Patented Feb. 17, 1920.

Application filed September 13, 1918. Serial No. 253,949.

To all whom it may concern:

Be it known that I, EDGAR C. MESSERSMITH, a citizen of the United States, residing in Buffalo, in the county of Erie and State of New York, have invented new and useful Improvements in Tripods for Mounting Guns, &c., of which the following is a specification.

This invention relates to a tripod which is more particularly designed for supporting a gun although the same may also be used for supporting other articles such as search lights which must be maintained in a definite position in order to obtain the desired results.

It is the object of this invention to provide a tripod of this character whereby the article to be supported may be properly and quickly mounted on any surface regardless of its contour and to accomplish this by means which can be readily and conveniently manipulated and accurately adjusted to any predetermined position as will hereinafter more fully appear.

25 In the accompanying drawings:

Figure 1 is a side elevation, partly broken away, of a tripod embodying my improvements. Fig. 2 is a vertical longitudinal section, on an enlarged scale, taken on line 2—2, Fig. 4. Fig. 3 is a vertical longitudinal section, on an enlarged scale, of the means for adjustably connecting the saddle and the adjusting arm of the tripod. Fig. 4 is a front elevation of the tripod, partly broken away. Figs. 5 and 6 are vertical transverse sections, on an enlarged scale, taken on the correspondingly numbered lines in Fig. 1. Fig. 7 is a horizontal section, on an enlarged scale taken on line 7—7, Fig. 4. Fig. 8 is 40 a fragmentary vertical longitudinal section, on an enlarged scale, taken on line 8—8, Fig. 4. Fig. 9 is a horizontal section, on an enlarged scale taken on line 9—9, Fig. 4. Fig. 10 is a fragmentary top plan view of 45 the worm gear wheel and the indicator or dial ring associated therewith. Fig. 11 is a vertical section, taken on line 11—11, Fig. 9.

Similar characters of reference refer to like parts throughout the several views.

50 1 represents the supporting head of the tripod upon which are arranged the various devices whereby the article to be supported may be adjusted horizontally and vertically to the proper position and which of itself is provided with means whereby the same may be supported in a normal position on the

ground or floor. The lower part of this head is constructed in the form of a downwardly projecting neck or shank 2, the opposite longitudinal sides 7 of which are vertical and parallel so as to form bearing faces while the upper part of this head is constructed in the form of an upwardly tapering or reduced stem 3.

The means for supporting this head on the ground or other surface comprises one inclined rear leg 4 and two inclined front legs 10 each of which is provided at its lower end with a shoe 11 adapted to engage the ground. The rear leg is provided at its upper front end with a coupling piece 5 of bifurcated form, the cheeks 6, 6 of which engage with the opposite vertical longitudinal bearing faces 7 of the supporting head, and this coupling piece is pivotally connected with this head so that the same may be turned in a vertical plane relatively to each other by means of a pivot pin 8 extending horizontally and transversely through the neck or shank of this supporting head. The pivot 8 of the coupling piece is preferably secured in the neck of the supporting head by means of pins 9 as shown in Fig. 7, or any other suitable means. The upper rear ends of the front legs may be adjustably connected with this supporting head in various ways but the means for this purpose shown in the drawings are preferred and comprise two coupling links 12, 12 each of which is adjustably connected at its lower end by means of a clamping bolt 15 with a coupling piece 16 at the upper end of one of the front legs while the upper end of this link is capable of rotary adjustment on a shank 13 arranged on one end of the pivot 95 pin 8 and is clamped with its inner side against the outer side of the adjacent cheek of the coupling piece by a screw nut 14 engaging with the outer end of the shank 13 and bearing against the outer side of the respective link, as shown in Fig. 7.

The axes of the pivot pin 8 and its shanks 13 are arranged horizontally and transversely and the axes of the clamping bolts 15, 15 are arranged lengthwise and substantially horizontally with reference to the tripod as a whole. By this means it is possible to first place the legs upon the ground in the most available position for bringing the supporting head to the desired height from the ground and then the head may be turned in a vertical plane relatively to all

of the legs so that it stands in a substantially upright or normal position best suited for operating the gun 80 mounted thereon. After the legs are thus properly placed on the ground the clamping nuts 14, 15 are turned so as to hold the front legs in the proper position relatively to the rear leg and the supporting head is also locked on the coupling piece of the rear leg so as to hold these parts in their proper relation. The locking means for holding the supporting head in position with reference to the coupling piece of the rear leg may be variously constructed but in the form shown in the drawings the same preferably comprises a segment 17 arranged on the rear part of the neck of the supporting head and provided with a row of V-shaped serrations 18, a locking dog or pawl 19 pivoted on the adjacent part of the coupling piece 5 by means of a transverse horizontal pin 20, so that the head is capable of swinging in a vertical plane lengthwise of the tripod and move the teeth or serrations 21 of the dog into and out of engagement with the serrations of the locking segment, and a clamping screw 22 arranged in a threaded opening in the upper part of the coupling piece 5 and engaging with the rear side of the dog for holding the latter in engagement with the locking segment, as best shown in Figs. 7 and 8.

Upon the upwardly tapering stem of the supporting head is pivotally mounted for rotation about a vertical axis a rotatable turret 23 which is preferably confined against upward movement on the stem 3 by means of a retaining screw 24 secured to this stem and a washer 250 interposed between the head of this screw and an upwardly facing shoulder on this turret. Means are provided whereby this turret may be first quickly turned into approximately a predetermined position and then slowly and exactly into the position desired. The preferred construction of these means are best shown in Figs. 1, 2, 5, 6, 8 and 9 and as there shown the same are constructed as follows:

25 represents a worm gear wheel mounted on the supporting head between its upwardly projecting stem and downwardly projecting neck. This worm wheel may be either formed integrally with the supporting head, as shown in the drawings, or the same may be made separate therefrom and connected therewith. Rotatably mounted on the turret is a worm 26 which engages with the worm wheel, so that upon turning this worm the turret and the parts mounted thereon will be shifted circumferentially relatively to the worm wheel. This worm is so mounted on the turret that the same can be either engaged with or disengaged from the worm wheel and thus permit the turret to be either turned quickly into its approxi-

mate predetermined position or turned slowly for bringing the same accurately into the desired position. For this purpose means are provided which preferably comprise a vertically and laterally-swinging yoke 28 which embraces the worm; an adjusting spindle or shaft 27 journaled horizontally on the lower part of this yoke and carrying the worm, and a horizontal pivot pin 29 connecting the upper part of this yoke with a bracket 31 which latter is secured to one side of the turret by means of a screw 30, as shown in Fig. 6. The yoke is moved toward and from the turret for the purpose of engaging and disengaging the worm and worm wheel by means of a shifting screw 32 engaging its thread with an internally-threaded opening in the bracket 31 and provided with an inner shoulder 33 adapted to engage with the inner side of the yoke and an outer hand wheel 34 engaging with the outer side of the same. By this means a turning movement of the shifting screw in one direction or the other will carry the yoke either toward or from the turret and thereby either engage the worm with or disengage the same from the worm wheel. The turning movement of the spindle 27 is effected by means of a hand wheel 320 applied to the front end thereof. In order to prevent dirt from getting into the teeth of the worm wheel and interfering with its operation the same is inclosed by a band or guard consisting preferably of two sections 470 connected by a screw 480 and mounted on the turret.

Means are provided for determining the relative position of the turret and the supporting head, this being preferably accomplished by means which comprise a horizontally rotatable dial ring 34 mounted on a circumferential shoulder 400 formed on the lower part of the turret and provided with a mark or indication 35 which is adapted to traverse a circumferential scale or row of graduations 36 on the adjacent upper surface of the worm wheel 25, as shown in Fig. 10. This dial ring 34 is preferably held frictionally in whatever position the same may be turned by hand on the turret, this friction being produced by means of a radially-movable detent plunger 37 arranged in a socket 38 in the periphery of the turret and held with its outer end yieldingly in engagement with a groove 40 in the bore of the dial ring by means of a spring 39 arranged in the socket and bearing at one end against the bottom of this socket and at its other end against the rear end of the detent plunger, as shown in Fig. 6. When using this dial ring the same is set with its mark or pointer 35 opposite the zero mark of the graduations 36 on the worm wheel. After a shot has been made with the gun mounted on the tripod and the

- observer gives instructions as to the number of points he wishes the turret to be turned horizontally for rendering the next shot more effective, then the operator shifts the 5 turret on the supporting head until the mark 35 has been moved in one direction or the other relatively to the zero mark on the wheel 25 in accordance with the instruction received from the observer.
- 10 For a similar purpose a dial mechanism is interposed between the worm shaft 27 and the yoke 28, so as to enable the attendant to turn the worm the required extent subject to instructions from the observer. The 15 dial mechanism associated with the worm spindle, as best shown in Figs. 2, 9 and 11, preferably comprises a longitudinally-split dial sleeve 41 mounted on the worm spindle in front of the yoke and provided at its rear 20 end with a flange 42 bearing an annular scale or row of graduations 43 which are adapted to register with a mark 44 on the adjacent part of the yoke. This dial sleeve is yieldingly held in position by means of 25 a spring-pressed detent 47 mounted in a socket 48 in the yoke and pressed with its front end against the inner side of the dial flange by means of a spring 49 arranged in this socket in rear of the detent 47, as 30 best shown in Fig. 9. When setting up this instrument, the dial sleeve is turned so that the zero mark on its dial plunger registers with the dial mark 44 on the yoke, and after one or more shots have been made from the 35 gun mounted on the tripod and the required correction has been determined, then the worm is turned until the graduations on one side or the other of the zero mark have traversed the stationary mark 44 the required distance. The dial sleeve is now 40 clamped permanently on the dial spindle, this being effected by connecting these split parts of the dial sleeve by means of a transverse screw 45 which upon being tightened 45 causes this sleeve to grip the worm spindle. This clamping screw preferably also engages a circumferential groove 46 in the adjacent part of the worm spindle, so that this screw serves as a key for preventing the dial sleeve 50 from moving lengthwise on the worm spindle.
- 55 Projecting rearwardly from the upper part of the turret are two coupling plates 50, 50, upon the rear ends of which are mounted a saddle 51 which carries the gun 80. The underside of this saddle is provided with two coupling plates 52 which engage with the outer sides of the coupling plates of the turret and are pivotally connected 60 therewith, so that the saddle may turn in a vertical plane. This is preferably accomplished by means of a shaft or spindle 53 passing through corresponding openings in the turret coupling plates and the saddle 65 coupling plates, said shaft being provided at one end with a handle 55 and with a shoulder 54 bearing against the outer side of one of the turret coupling plates, while its opposite end is provided with a screw 56 bearing against the outer side of the other 70 saddle coupling plate. The saddle also is provided with an adjusting arm 63 which projects rearwardly from the pivot 53. Between the saddle and the turret are arranged means for coarsely and accurately adjusting 75 the position of the saddle with reference to the turret. These means for effecting the coarse adjustment between the turret and saddle are preferably constructed as follows:
- 80 57 represents an adjusting arm arranged with the hub at its front end between the two coupling plates of the turret and mounted on the shaft 53. One side of the hub of this adjusting arm bears against the inner side of one of the turret coupling plates and on its opposite side this hub is provided with a conical recess or socket 58 which is arranged concentric with the axis of its hub. Engaging with this conical socket is a conical clamping disk or cone 59 which is provided in its bore with an internal screw 85 thread engaging with an external screw thread 62 on the adjacent part of the adjusting shaft 53, and also provided on its outer 90 side with a key 61 which engages with a seat 60 on the inner side of the outer turret coupling plate, as best shown in Fig. 5. Upon turning the shaft 53 in one direction, the clamping cone 59 will be drawn into the 100 socket of the adjusting arm and press the latter against the inner side of the adjacent turret coupling plate, while upon turning this shaft in the opposite direction the grip of the cone on the hub of this adjusting arm 105 will be released and thereby permit the adjusting arm 57 to be turned with reference to the turret. By this means the saddle and the adjusting arm 57 may be turned simultaneously about the shaft 53 for roughly positioning the gun on the saddle relatively to the turret and then the adjusting arm 57 is clamped on the turret, but still leaving the saddle to swing freely on the turret. The means for effecting the fine adjusting of the 110 saddle with reference to the turret is interposed between the rear ends of the saddle arm 63 and the turret arm 57, these means as shown in Figs. 1 and 3 being preferably constructed as follows:
- 115 64, 640 represent upper and lower end screw members of a turn buckle, which members are preferably provided with internal right and left hand screw threads and pivotally connecting respectively with the rear 120 ends of the saddle arm and turret arm by means of pins 75, 76. 65 represents an intermediate screw member forming part of the turn buckle, which member is provided at its opposite ends with external right and 130

left-hand screw threads engaging with the corresponding screw threads in the upper and lower end members. This intermediate screw member is preferably manipulated by means of a hand wheel 66 secured to the central part thereof. For the purpose of determining the amount of fine adjustment which is required between the saddle and the turret after the coarse adjustment has been effected, a dial or indicating mechanism is provided which is preferably constructed as follows:

67 represents a dial ring rotatable on an annular shoulder 90 formed on the hand wheel 66 and provided on its peripheral surface with an annular row of graduations 71. This dial ring is retained on this hand wheel by engagement of its lower end with the shoulder 90 while its upper end engages with a retaining plate 68 secured to the upper end of the hand wheel. 70 represents a pointer which is arranged on the upper screw member of the turn buckle and serves as a mark with reference to which the dial ring 67 on the hand wheel may be turned. Preparatory to making a shot with a gun after the same has been set up, the dial ring 67 is turned with its zero mark in line with the pointer 70. After this the hand wheel 66 is turned so that the scale or graduations of this dial ring are moved from one side or the other of the pointer in accordance with the instructions received from the observer for aiming the gun, thereby causing the saddle to be tilted in one direction or the other and changing the angle of the gun in accordance with the instructions of the observer, so that the shot from the gun will become effective. The dial ring 67 is frictionally held in its adjusted position on this hand wheel by means which preferably consists of a detent ball 72 arranged in a socket 73 in the hub of this hand wheel and pressed against the inner side of the dial ring by means of a spring 74 which is preferably of leaf form and is interposed between the rear side of this socket and the rear side of this detent ball.

These various improvements permit of rapidly and easily adjusting the gun so as to permit the operator of the same to hit the objective when the gun is fired, which means are so designed that they can be produced at comparatively low cost and are not liable to get out of order under ordinary conditions.

I claim as my invention:

1. A tripod comprising a leg provided with a coupling piece, a supporting head pivoted on said coupling piece, and means for locking said supporting head and coupling piece in position relatively to each other comprising a segment arranged on said head and having a serrated periphery, a locking dog pivoted on said coupling piece

and having a serrated face engaging the serrations of said segment, and a clamping screw mounted on said coupling piece and engaging with said dog.

2. A tripod comprising a supporting head, a turret rotatable horizontally on said head and means for rotating said turret comprising a worm wheel arranged on said head, a worm meshing with said worm wheel, a bracket arranged on said turret, a yoke pivoted on said bracket to swing laterally and carrying said worm, and a shifting screw connecting said yoke and said bracket.

3. A tripod comprising a turret, an adjusting arm mounted on said turret so as to be capable of swinging vertically and provided with a conical clamping socket, a clamping cone engaging with said clamping socket, a clamping screw pivotally connecting said turret and arm and adapted to move said cone and socket toward and from each other and a saddle mounted on said turret and adjustably connected with said arm.

4. A tripod comprising a turret, an adjusting arm adjustably pivoted on said turret, a saddle adjustably pivoted on said turret, and means for adjusting said saddle relatively to said arm comprising two end screw members connected with said saddle and arm, respectively, an intermediate rotatable screw member engaging with said end screw members, a pointer arranged on one of said end screw members, and a dial rotatable on said intermediate screw member and provided with graduations adapted to register with said pointer.

5. A tripod comprising a supporting head, a worm wheel mounted on said head and provided with graduations, a turret rotatable on said head, and a dial rotatable on said turret and provided with a mark adapted to register with said graduations.

6. A tripod comprising a supporting head, a worm wheel mounted on said head, a turret rotatable on said head, a worm engaging with said worm wheel, a spindle carrying said worm, a bearing which is mounted on said turret and in which said spindle turns and provided with a mark, and a dial rotatable on said spindle and provided with graduations adapted to register with said mark.

7. A tripod gun mount comprising a pintle, legs adjustably connected to said pintle, the upper portion of said pintle being tapered, a head provided with a socket to receive said tapered portion of said pintle, means for locking the head to said pintle, a rearwardly extending arm secured in said head, and capable of angular adjustment with regard to said head, a cradle also mounted in said head and capable of angular adjustment with regard to said head and said rearwardly extending arm, and means

- for locking the said rearwardly extending arm and said cradle with relation to said head.
8. A tripod gun mount having a pintle pivotally mounted and capable of swinging about a transverse horizontal axis, said pintle having a supporting base-plate circumferentially arranged thereon, a head rotatably mounted on said pintle and supported in said base-plate, bracket arms secured to said head, a rearwardly extending arm mounted in said bracket arm capable of adjustment with regard to said bracket arm, and a cradle also mounted in said bracket arms and capable of adjustment with regard to said bracket arms and to said rearwardly extending arm.
9. A tripod gun mount comprising a pintle, legs for supporting said pintle and said pintle pivotally mounted with regard to said legs, said pintle provided with a circumferentially arranged base-plate, a rotatable head mounted on said pintle and supported in said base-plate, the circumferential base plate being provided with annularly arranged teeth, means mounted on said head for co-operating with said teeth to rotate the said head, a rearwardly extending arm mounted in said head, a cradle mounted in said head, means connected to the rear of the cradle and the rear of the supporting arm for adjusting the cradle with relation to the rearwardly extending arm.
10. A tripod gun mount comprising a pintle, legs connected to and supporting said pintle, a base-plate circumferentially formed on said pintle, a graduated circumferential dial marked on said base-plate, a head rotatably mounted on said pintle and supported in said base-plate, an index-ring carried by said head and normally held in frictional contact with said head to thereby rotate with said head, but capable of being rotated manually when desired to set the index point opposite any graduation on the dial, and a cradle mounted on said head and capable of movement about a transverse horizontal axis.
11. A tripod gun mount comprising in part a pintle, said pintle provided with a circumferentially arranged base-plate and said base-plate having annular grooves arranged therein, a plurality of teeth formed on the outer periphery of said base-plate, a head rotatably mounted on said pintle and said head provided with a base, said base resting in said annular grooves arranged in said base-plate, and means for securing the head to said pintle.
12. A tripod gun mount comprising in part a head, a horizontally extending bracket arm secured to said head, a guard-ring secured to said bracket arm, a casing secured to said bracket arm, said casing having a worm operatively mounted therein and means for swinging the casing and worm toward and away from said head.
13. A tripod gun mount comprising in part a pintle, said pintle provided with a plurality of teeth about its outer circumference, a head provided with a socket to fit over said pintle and said head adapted to rotate on said pintle, a guard-ring carried by said head surrounding said teeth on said base-plate, and said guard-ring provided with an opening therein, a dial marked on the base-plate of said pintle, an index-ring carried by said head and normally held in frictional contact with said head, and free to be set at any desired point, a worm pivotally mounted to said head and a portion thereof adapted to pass within the opening in said guard-ring, means for throwing the worm into and out of contact with the teeth on said pintle, and means for operating said worm when said worm is in contact with the said teeth to thereby rotate said head.
14. A tripod gun mount comprising in part a pintle, said pintle provided with a circular base-plate, a head rotatably mounted on said pintle and supported in said base-plate, a bracket arm extending outwardly from said head, a downwardly extending casing pivotally mounted to said outwardly extending bracket arm, a shaft extending into said casing and a worm mounted on said shaft, a graduated dial mounted in said casing and normally clamped to said shaft to rotate with the same and said dial capable of being loosened from said shaft so that the same may be set in any desired position.
15. A tripod gun mount comprising in part a cradle, a rearwardly extending arm, an elevating mechanism secured to the rear of said cradle and rearwardly extending arm, said elevating mechanism comprising an upper and lower post and a casing operatively connected with said posts to force said posts toward and away from each other, and a dial loosely mounted around said casing, means for holding said dial in contact with said casing, and said dial capable of being rotated manually to any desired point.
16. A tripod gun mount comprising legs, a pintle, a head rotatably mounted on said pintle, a rearwardly extending arm mounted in said head, a cradle also mounted on said head, a rear elevating mechanism adjustably connected to said cradle and pivotally connected to said rearwardly extending arm, means on said rear elevating mechanism for determining the amount of movement between said cradle and said rearwardly extending arm.
